CLAIM

The ornamental design for a personal wireless communicator, as shown and described.

DESCRIPTION

FIG. 1 is a top, front, and right side perspective view a personal wireless communicator showing our new design; FIG. 2 is a left side elevational view thereof; FIG. 3 is a bottom plan view thereof; and, FIG. 4 is a rear elevational view thereof.

The antenna is shown in broken lines and is for illustrative purposes only, and forms no part of the design.
